CLAIM

The ornamental design for a display screen or portion thereof with graphical user interface for display of workflow tasks, as shown and described.

DESCRIPTION

The sole FIGURE is a front view of a display screen or portion thereof with graphical user interface for display of workflow tasks showing our new design.

The dashed line shown as part of an icon is a claimed element of the design. The broken line showing of the display screen or portion thereof and the remainder of the graphical user interface forms no part of the claimed design.

1 Claim, 1 Drawing Sheet

The screenshot shows a digital interface for creating a workflow step. At the top, there are navigation buttons: a 'New' button, a 'Help' icon, and a 'Logout' button. Below these are tabs for 'Dashboard', 'Tasks (1)', and 'Workflows'. A 'Create Step' wizard is open, with the first step 'General' selected. The wizard has a progress bar at the top right showing '1 Step Complete' and '2 Steps Remaining'. The main area displays five task options:

- General**: Create instructions for a 124x240px image. Options: Add to My Content Library, Use Template.
- Content Approval**: Create approval steps for your report. Options: Create Approval, Use Template.
- Content Upload**: Upload files to your dashboard. Options: Add to My Content Library, Use Template.
- Content Feedback**: Create feedback for your report. Options: Add to My Content Library, Use Template.
- Content Edit**: Edit report cards from your dashboard. Options: Add to My Content Library, Use Template.

At the bottom right of the wizard, there are buttons for 'Create Another Step' and 'Create Step'.
